UNITED STATES PATENT OFFICE.

PERKINS O. HATFIELD, OF NEW ORLEANS, LOUISIANA.

STANDARD.

987,718.

Specification of Letters Patent. Patented Mar. 28, 1911.

Application filed May 31, 1910. Serial No. 564,099.

To all whom it may concern:

Be it known that I, PERKINS O. HATFIELD, a citizen of the United States, residing at New Orleans, in the parish of Orleans and 5 State of Louisiana, have invented certain new and useful Improvements in Standards, of which the following is a specification, reference being had to the accompanying drawings.

10 My invention relates to improvements in releasable stakes or standards for log cars, wagons and other vehicles.

One object of the invention is to provide an improved stake or standard fastening 15 means which will be strong and durable and capable of being quickly and easily released.

Another object of the invention is to provide a stake or standard fastening means with an improved releasing or throw off 20 device whereby a load of logs etc. may be readily released or dumped without danger to the operator.

With the above and other objects in view, the invention consists of the novel features 25 of construction, combination and arrangement of parts hereinafter fully described and claimed, and illustrated in the accompanying drawings in which—

Figure 1 is a side elevation of a beam or 30 bolster showing one embodiment of my invention applied thereto; Fig. 2 is a top plan view of the same; Fig. 3 is an end view; Fig. 4 is a detail perspective view of one of the standards; Fig. 5 is a detail perspective 35 view of a portion of the bolster showing a modified form of my invention applied thereto; Fig. 6 is a plan view of the parts shown in Fig. 5; and Fig. 7 is a detail cross sectional view taken on the plane indicated 40 by the line 7—7 in Fig. 6.

Referring more particularly to Figs. 1 to 4 inclusive of the drawings, 1 denotes a bolster or beam of a logging car, wagon, sled or other vehicle and 2 denotes one of my 45 improved stakes or standards which latter may be mounted on either or both ends of the bolster. This standard is in the form of a straight, flat metal bar pivotally mounted to swing on a transverse horizontal pivot 3 and disposed in a vertical notch or recess 4 in one end of the standard. By mounting the bolster in this manner it may swing outwardly and downwardly to release the load. When the bolster is made of wood its ends 50 may be surrounded by one or more reinforcing or wear plates 5 as shown.

The standard 2 is retained in its upright position by a chain or other flexible element 6 the intermediate portion of which engages a shoulder 7 in the form of an integral 60 outwardly projecting lug or hook formed on the outer edge of the standard as shown more clearly in Fig. 4. One end of the chain 6 is suitably anchored and its other end adapted to be releasably secured. Such 65 releasable free end carries an elongated eye or link 11 adapted to fit over an eye 10 projecting transversely from one side of the bolster. This eye 10 is preferably in the form of an eye bolt the body portion 9 of 70 which passes transversely through the bolster and the projecting opposite end of which serves as the fastening means for the anchored end of the chain 6 as will be seen on reference to Figs. 1, 2 and 3, a retaining 75 nut 8 being applied to the other end of the eye bolt.

12 denotes a locking member for the chain in the form of a pin which is inserted in the outer portion of the keeper eye 10 after the 80 link 11 has been placed thereon. To prevent the loss of the pin 12 it may be connected by a chain 13 to a staple or eye 15 on the bolster.

14 denotes a releasing or throw off member 85 arranged in the inner portion of the keeper 10 and adapted to be actuated in the outward direction to move the link 11 off of said eye after the locking member or pin 12 has been removed. This releasing member 90 14 is preferably in the form of a lever one end of which may be pivotally mounted on the bolster by means of the staple 15 or any other suitable means and the intermediate portion of which extends through the eye 10. 95 The free end of the lever 14 is preferably offset as shown at 16 and provided with an outwardly projecting handle 17.

In the embodiment of the invention illustrated in Figs. 5, 6 and 7 of the drawings 100 the keeper or keeper eye 10^a is in the form of a staple and the locking member or pin 12^a which is formed by an angularly bent end of a swinging arm 18 pivoted at 19 on one side of the bolster. The swinging arm 105 18 or lever 18 has a straight vertically extending portion arranged beneath the curved or offset portion 16^a of the releasing member or lever 14^a whereby when the arm 18 is swung inwardly to move the locking pin 12^a out 110 of the keeper eye 10^a the releasing member or lever 14^a will also be actuated in an out-

ward direction to throw the chain link 19 off of the eye 10^a. Owing to this construction it will be seen that the curved offset portion 16^a serves as a cam for engagement 5 by the arm 18 when the latter is swung inwardly to releasing position. Any means may be provided for actuating and locking the arm or member 18 but I preferably employ a link or rod 20 which extends longitudinally of the bolster so that the stake may 10 be released from the side of the car opposite to the one on which the stake is mounted. This rod 20 has one of its ends pivoted at 21 to the arm or member 18 and on its free end is a loop or other suitable handle 22. Its intermediate portion is bent or offset to 15 form a shoulder 23 which is adapted to drop into engagement with the lower portion of a supporting and guide staple 24 arranged 20 on the bolster and through which said rod 20 extends. When the offset 23 is arranged in the staple 24 as shown in Fig. 5 the latter serves as a keeper to lock the rod 20 against 25 longitudinal movement and consequently locks the arm 18 and locking pin 12^a in effective position. When it is desired to release the stake or standard 2^a it is only necessary to grasp the handle 22 lift it slightly and then pull the rod 20 longitudinally to swing 30 the arm 18 inwardly whereupon the pin 12^a moves out of the lever 14^a and the straight portion of the arm 18 actuates the lever 14^a to cause it to push the chain link 11^a off of the eye 10^a. 35 Various changes in the form, proportion and arrangement of parts may be made within the spirit and scope of the invention.

I claim—

1. A wagon bolster having a keeper eye 40 projecting laterally from one side thereof, in combination with a standard having its lower end pivotally connected to the bolster, said standard being provided with a shoulder on its outer side, a flexible element having a 45 link at one end to engage said keeper eye, and having its opposite end anchored to the opposite side of the bolster, a locking member for insertion in said keeper eye on the outer side of said link, and a releasable member pivotally connected at one end to that 50 side of the bolster from which the keeper eye extends, the said releasable member extending through and being guided by the said keeper eye, and enabling the link, when

the locking member has been disengaged, to 55 be moved outwardly on, and released from the keeper eye.

2. In a device of the character set forth, 60 the combination of a bolster, a releasable standard thereon, a keeper eye on the bolster, a flexible element to engage the standard having one end anchored and its other end provided with a link to engage said eye, a movable releasing member extending through the inner portion of the eye and having a 65 cam surface, and a swinging member having a portion to co-act with the cam surface on the releasing member and a portion to enter the outer end of the eye and lock the link upon the latter. 70

3. In a device of the character set forth, 75 the combination of a bolster, a releasable standard thereon, a keeper eye on the bolster, a flexible element to engage the standard having one end anchored and its other end 80 provided with a link to engage said eye, a movable releasing member extending through the inner portion of the eye and having a cam surface, a movable member having a portion to co-act with the cam surface on said releasing member and a portion to enter the outer end of the eye to lock the link thereon and means for actuating and locking the last mentioned movable member. 85

4. In a device of the character set forth, 90 the combination of a bolster, a releasable standard thereon, a keeper eye on the bolster, a flexible element to engage the standard having one end anchored and its other end provided with a link to engage said eye, a movable releasing member extending through the inner portion of the eye and having a cam surface, a swinging member pivoted at one end to the bolster and having a portion to co-act with the cam surface on 95 said locking member and the end portion to enter the outer end of said eye to lock the link upon the latter, a guide and keeper upon the bolster and a rod connected to said swinging member and having a shouldered 100 portion to co-act with said guide and keeper.

In testimony whereof I hereunto affix my signature in the presence of two witnesses.

PERKINS O. HATFIELD.
